[57] CLAIM

The ornamental design of a folding keyboard pad, substantially as shown and described.

DESCRIPTION

FIG. 1 is a top-right perspective view of a folding keyboard pad showing the new design in an open position; FIG. 2 is a top view of the new folding keyboard pad design in the open position;

FIG. 3 is a right-rear perspective view of the new folding keyboard pad design in the closed position;

FIG. 4 is a right side edge elevational view of the keyboard pad in the closed position, and is a mirror image of a left side edge elevational view; and

FIG. 5 is a front edge elevational view of the keyboard pad in the closed position.
